LIQUID PURIFIER

Milton Baruch, Los Angeles, Calif.

Application June 15, 1936, Serial No. 85,319

6 Claims. (Cl. 210—131)

This invention relates to a liquid purifying means, and pertains particularly to a device which will receive a flow of liquid and subject the same to a purifying operation, such as filtration, clarification, decolorization, deodorization, or the like.

The principal object of the invention is to provide an apparatus provided with a removable purifying element, in which such element may be removed from the main body of the device and a new element replaced therein in a quick and facile manner.

A further object of the invention is to provide a device of the character described, which is adapted to handle a relatively large quantity of liquid per unit of time in a given size of apparatus, and at a relatively low pressure drop.

A further object of the invention is to provide an advantageous form of removable purifying element for a device of the character described.

The device of the present invention may comprise, essentially, an external container member provided with a recess, preferably of cylindrical shape, adapted to receive a removable self-contained purifying element provided with a central liquid outlet passage, suitable liquid inlet and outlet connections being provided for the external container member, said outlet connection being preferably associated with a perforate liquid discharge sleeve secured to the lower end of said container member and adapted to extend within the aforesaid outlet passage into a position substantially surrounded by said purifying member. The purifying member may comprise a cylindrical container provided with an opening in one end communicating with said liquid outlet passage and adapted to receive said liquid discharge sleeve, said liquid outlet passage being defined by a tubular fluid pervious member secured to said container at the end thereof adjacent the aforesaid opening, and extending axially within the container in position to surround said perforate liquid discharge member when the purifying element is in position within the external container. The space between the tubular fluid pervious member and the side walls of the purifying element is filled with a suitable liquid purifying material, such as a fibrous filter mass, or a body of decolorizing clay or other comparable material. The side walls of the purifying element are provided with a plurality of liquid inlet openings, preferably disposed adjacent the end thereof opposite said one end, and communicating with the interior of the external container.

Other objects and features of the invention will

be brought out in the ensuing description of a preferred embodiment thereof, or will be apparent from such description. The accompanying drawings illustrate such a preferred embodiment, and referring thereto:

Fig. 1 is a plan view of the device, with the head portion thereof broken away to show the upper wall of the removable purifying element;

Fig. 2 is a partly broken away side elevation thereof, showing the contained removable purifying element, said element being also partly broken away at each end to show the internal construction thereof;

Fig. 3 is a plan section taken on line 3—3 in Fig. 2;

Fig. 4 is a transverse sectional detail of one side of the discharge end of the removable purifying element, showing constructional features thereof; and

Fig. 5 is a partly broken away perspective view of a removable purifying element of the present invention.

Referring to the drawings, a cylindrical body member or external container is shown at 1 provided with a lower wall 2 having a fluid outlet connection 3 and a removable upper wall or head 4 secured to the member 1 through the agency of a plurality of stud bolts 5 and wing nuts 6. The bolts 5 are preferably secured to the container 1 as by casting said container about the knurled lower ends 5a of said bolts, according to conventional practice. A suitable gasket member 7 is preferably provided at the upper end of the container 1 in position to be engaged by the head member 4 to effectively seal the external container, said gasket being conveniently disposed in a suitable annular recess 7a in the lower surface of the head 4. A liquid discharge member is provided within the container 1 and may comprise a cylindrical sleeve 11 provided with a plurality of perforations 11a in the side walls thereof as shown particularly in Fig. 3, and extending axially upwardly within the cylindrical space defined by the side walls of the container 1 to a point adjacent the upper end of said container. The perforate sleeve 11 is preferably disposed about a suitable supporting member such as an upwardly projecting "cross" shaped member 12 provided with recesses or passages 12a extending along the length of said member. Said supporting member may be secured at its lower end to, or formed integrally with, a foot member 13 of circular shape which is in turn secured to the lower wall 2 in any suitable manner, as through the agency of an upstanding

collar 2a formed in said wall and rolled over the outer edge of a peripheral bead 13a formed on said foot member. Where the purifying device is not subjected to very great pressures, the 5 supporting member 12 may be dispensed with, and the sleeve 11 secured to the foot member 13 in any suitable manner. The upper end of the member 12 may be provided with a projecting portion 14 of reduced diameter and carrying a 10 washer or the like 15 engaging the upper end of the sleeve 11, the outer end of the projection 14 being riveted over to secure the washer 15 in position. A plurality of openings 16 are provided in the foot member 13 interiorly of the 15 sleeve 11 and establishing communication between the recesses 12a and the liquid discharge connection 3, said openings constituting the only means for outflow of liquid from the interior of the container to the discharge connection 3. A 20 suitable drain plug or the like may be provided as at 17 at the lower wall of the container 1 if desired.

The removable purifying element may comprise a cylindrical container 21 provided with a 25 closed upper end wall 22 provided with a bail 23 in position to be grasped manually when the head 4 is removed from the device. The lower wall of the container 21 is provided with a suitable 30 opening through which the perforated discharge member 11 may extend, and a tubular fluid-pervious member is provided for said container, secured to the lower wall thereof adjacent the aforesaid opening and extending axially upwardly through said container to a point adjacent the 35 upper end thereof, in position to surround the sleeve 11. The tubular fluid-pervious member or liquid outlet passage may comprise a fabric sock 24 having a closed upper end 25 and extending through an opening 26 at the center of an inner 40 wall member 27 at the lower end of the container 21. The wall member 27 is secured to the side walls of the container 21 in any suitable manner as by means of a conventional form of roll seam provided for the ends of a tin can. Such a 45 construction is shown in larger scale detail in Figs. 4 and 5. The lower end of the sock 24 is bifurcated or split into a plurality of strips 24a which are stretched or splayed outwardly over the rim 27a of the inner wall 27 and secured to 50 said wall through the agency of an outer wall member 28 which is secured to the rim portion 27a of the inner wall 27 in the same manner as said inner wall is secured to the side walls 21a of the container 21. A suitable opening 29 is 55 provided at the center of the wall 28 in line with the opening 26 above described and a portion of the metal of the wall 28 may be rolled upwardly within the sock 24, as shown at 31, to secure said sock firmly at the position of the aforesaid openings 26 and 29. Other forms of construction may, 60 of course, be employed for connecting the lower end of the pervious tubular member 24 to the lower end wall of the container 21.

The interior of the container 21, that is, the 65 space between the sock 24 and the side walls 21a of said container, is preferably substantially completely filled with a mass of purifying material which may comprise a body of fibrous material such as paper pulp or a porous mass of decolorizing 70 ing material such as fuller's earth or the like, or mixtures of such materials, dependent upon the particular purifying problem at hand. The side wall 21a of the container 21 is provided with suitable liquid inlet means such as a plurality of openings 75 32 arranged in a plurality of rows or in any

other convenient manner, to provide for inlet of liquid into the interior of said container. The openings 32 are preferably disposed adjacent the upper end of the container 21. The mass of purifying material, designated at 33, is preferably 5 spaced from the side wall 21a of said container in some suitable manner as, for example, through the agency of a helical wire spacer 34 and a screen member 35, to allow free access of the incoming liquid to the full length of the purifying body. In 10 the event that a clay or comparable material is employed for the purifying body, I preferably provide a closely woven or fine-grained fluid-pervious membrane 36 interiorly of the screen 35 to prevent dusting of the material from the body 15 33. The membrane 36 may be formed of fabric if desired, although I have found a thin, pervious cellulosic material comparable to the sheet material obtainable under the trade name "Kleenex" 20 to be highly advantageous when an oleaginous liquid is to be passed through the purifier. A thin sheet of such a cellulosic material may be secured in place against the screen 35 before the interior of the container is filled with the body 33, 25 as by dampening the screen 35 with a suitable adhesive such as sodium silicate solution, pressing the membrane 36 against the inner surface of said screen and allowing the adhesive to dry.

The container 1 is provided with a liquid inlet connection 41 opening into the interior of said container as at 42, and suitable means are preferably provided for varying the size of the inlet opening, as by means of a screw 43 threadedly disposed in the side wall of the container, in position to extend across any desired portion of 35 the opening 42. A suitable lock nut or the like is preferably provided as at 44 to secure the screw 43 in an established position. The liquid inlet connection is preferably located adjacent the upper end of the container 1, somewhat after the 40 manner shown, but the specific location of this inlet is purely a matter of choice, as will be apparent to one skilled in the art.

In assembling the removable purifying element, I may utilize a conventional tin can closed at one 45 end and open at the other, an opening 26 being provided for the closed end of the can, which closed end will constitute the wall 27. The sock 24 is then inserted within the opening 26 and the open end thereof splayed out over the said lower 50 wall after the manner shown in Figs. 3 and 5, a center-perforated conventional can lid 28 being then rolled into engagement with the rim of the can over the splayed ends of the sock, to engage the rim 27a of the wall 27, and the central portion 55 of said lid being rolled inwardly as above described to securely engage the sock at the position of the openings 26 and 29. A mandrel may then be inserted within the sock 24, simulating the position of the sleeve 11, the helical support or spacer 34 placed in position against the side wall 21a of the can, and the screen 35 and the membrane 36 placed in position against the spacer 34. The space between the membrane 36 and the sock 24 60 is then filled with the purifying body 33, and the upper wall 22 then placed over the open end of the can and rolled into secure engagement with the upper edges of the side wall 21a in the same manner as the ordinary tin can is capped in a 65 canning operation. The mandrel may then be withdrawn, and, assuming the holes 32 to have been previously formed in the side wall 21 of the can, the purifying element is ready for use.

The axial length of the container 21 is so 70 selected with respect to the interior axial length 75

of the container 1 as to provide sealing engagement with the lower wall 28 of the container 21 against a gasket member 46 which is in turn forced into firm engagement with the upper surface of the foot member 13 when the head 4 is forced downwardly to take up on the gasket 1, a suitable shoulder means such as a boss or projection 47 being provided on the lower face of the wall 4 in position to engage the upper wall 22 of the can 21 to force the purifying element downwardly into sealing engagement with the gasket 46. Minor variations in the axial length of the container 21 are readily accommodated by the resilience of the head 22.

In the operation of the device, the liquid to be purified is admitted at 42, enters the purifying element through the openings 32 whence it may flow downwardly along the full length of the side wall 21a as above described, and enters the purifying body 33 in a radial direction along substantially the full length of the membrane 36. The liquid is subjected to the purifying treatment in passing inwardly toward the sock 24, and the purified liquid enters the space within the sleeve 11 through the openings 11a and is withdrawn from the device through the openings 16 and connection 3. When it is desired to replace an exhausted purifying element it is merely necessary to stop the flow of liquid, remove the wing nuts 6, lift the head 4 from the container 1, grasp the purifying element by means of the bail 23 and lift the same from the container 1. The new purifying element is placed within the container 1 by a reverse procedure, and the entire operation of removing and replacing the purifying element may be carried out in less than a minute's time. The device is primarily adapted for use on internal combustion engines, and the facile replacement of the purifying element makes it possible to remove and renew the purifier without the aid of skilled labor. A suitable bracket or the like may be provided as shown at 51, to secure the purifying device to a suitable supporting structure adjacent the engine with which the device is associated, as will be apparent to one skilled in the art.

In the above specific description of the present device I have considered that the cylindrical container 1 is disposed substantially vertically in use. It will be appreciated that the device might equally well be disposed at an angle to the vertical without departing from the spirit of the invention. Furthermore, while the liquid discharge member 11 is shown as extending upwardly from the lower wall of the container 1, it will be appreciated that the construction may be inverted, or the member 11 may be secured to the upper wall 4 of the device, within the contemplation of this invention. In general, it is more convenient to provide both the liquid inlet and outlet connections on the relatively fixed portion of the device, as upon the container 1 as shown, whereby it is not necessary to remove such a connection in the operation of replacing the removable purifying element.

The removable purifying element is most advantageously formed of circular cross-section, whereby conventional canning machines may be utilized in assembly thereof, but at the same time it will be realized that the specific cross-sectional configuration of the element is a matter of choice, and as far as the operational characteristics of the device are concerned, a cross-section other than circular may be employed.

In like manner, the shape of the external con-

tainer is not necessarily restricted to cylindrical, although in view of the fact that the device is ordinarily required to withstand a modicum of internal pressure a cross-section of circular shape provides economies in fabrication, as will be apparent to one skilled in the art of metal working. Other obvious modifications of the device are clearly contemplated, and I do not choose to be restricted to the specific construction herein delineated and described, but rather to the scope of the appended claims.

I claim:

1. A liquid purifying device comprising: an upwardly extending external container having a substantially cylindrical side wall, a bottom wall, and an open upper end; a closure member removably secured to the top of said side wall in position to close the upper end of said container; said bottom wall being provided with a central liquid outlet opening; a perforate tubular liquid discharge member secured to the bottom wall around said opening and communicating therewith and extending axially upwardly within said container; a removable purifying element disposed within said container and freely removable through said open upper end thereof and provided with a perforate outer wall spaced from the side wall of said container, a closed top wall, a bottom wall having a central opening, a centrally disposed tubular fluid pervious member secured to said last-named bottom wall around the central opening therein and extending upwardly around said tubular liquid discharge member in freely removable relation thereto and closed at its upper end, and a pervious body of purifying material disposed within the walls of said purifying element and around said tubular fluid pervious member; said external container being also provided with a liquid inlet opening communicating with the space between said container and said purifying element.

2. A liquid purifying device as set forth in claim 1, said liquid inlet opening being provided in the side wall of said container adjacent the upper end thereof.

3. A liquid purifying device as set forth in claim 1, and further comprising sealing means disposed around the lower portion of said tubular fluid pervious member in engagement with the bottom wall of said purifying element, and means on said closure means engaging the upper end of said purifying device to hold said bottom wall thereof in compressive engagement with said sealing means.

4. A removable purifying element for liquid purifying devices, which comprises: a substantially cylindrical container member provided with perforate side walls and with a wall member closing one end of said container and a center-perforated wall member at the other end of said container; a tubular fluid pervious member secured to said last-named wall member and extending axially inwardly of said container from the central perforation in said wall member; a body of pulverulent purifying material within said container and surrounding said tubular member; and a fluid pervious membrane disposed about said body of material and spaced from the side walls of said container, through the agency of a screen member surrounding said membrane and a helical wire member surrounding said screen member, said membrane being affixed to said screen member.

5. A removable purifying element for liquid purifying devices, which comprises: a container

provided with a closed wall at one end and a substantially cylindrical side wall provided with fluid-inlet perforations; a center-perforated inner wall member extending transversely across the other end of said container and having a rim portion secured to said side wall; a tubular fluid-pervious member extending inwardly of said container through the opening in said inner wall member and having a portion extending exteriorly of said inner wall member; an outer wall member overlying and secured to said inner wall member, said outer wall member being positioned in engagement with said exteriorly extending portion of said tubular member to force the same inwardly into engagement with the outer surface of

said inner wall member and position said tubular member with respect to said container, and said outer wall member being provided with a fluid discharge opening aligned with said tubular member; and a body of purifying material within said container and surrounding said tubular member.

5. The removable purifying element set forth in claim 5, said exteriorly extending portion of said tubular member being bifurcated and splayed outwardly from said opening in said inner wall member and secured between said rim portion of said inner wall member and said outer wall member.

MILTON BARUCH.
